(57) **CLAIM**

The ornamental design for all-terrain vehicle tire, as shown and described.

DESCRIPTION

FIG. 1 is a perspective view of all-terrain vehicle tire, showing my new design;

FIG. 2 is a front view thereof;

FIG. 3 is a left view thereof;

FIG. 4 is a partial enlarged view of FIG. 2;

FIG. 5 is a partial enlarged view of FIG. 3; and,

FIG. 6 is a cross-section view taken along the line A-A in FIG. 2.

The broken lines indicating enlarged portions of the all-terrain vehicle tire, form no part of the claimed design.
